UNITED STATES PATENT OFFICE.

FLETCHER B. HOLMES, OF WOODBURY, NEW JERSEY, ASSIGNOR TO THE EASTERN DYNAMITE COMPANY, OF WILMINGTON, DELAWARE, A CORPORATION OF NEW JERSEY.

HIGH EXPLOSIVE AND PROCESS OF MAKING THE SAME.

No. 861,177.

Specification of Letters Patent.

Patented July 23, 1907.

Application filed March 30, 1906. Serial No. 308,978.

To all whom it may concern:

Be it known that I, FLETCHER B. HOLMES, a citizen of the United States, residing at Woodbury, county of Gloucester, and State of New Jersey, have invented 5 a new and useful Improvement in High Explosives and Process of Making the Same, of which the following is a full, clear, and exact description.

My invention relates to those non-freezing pulverulent powders which contain an ungelatinized nitrated 10 carbo-hydrate, for instance, nitro-cotton, nitro-starch and nitro-cellulose, as the whole or a prominent part of the explosive and also contain a solid inorganic oxidizing agent.

My invention consists in an improved explosive, of 15 this character, in which the explosive is rendered water-proof without substantially impairing its sensitiveness.

My invention also consists in the process by which this improved explosive is produced.

20 My improved explosive is an uncompressed, waterproof, pulverulent explosive consisting of a mixture of ungelatinized nitrated carbo-hydrate and a solid inorganic oxidizing agent and in which, throughout the explosive, substantially only the surfaces of the 25 particles of nitrated carbohydrates are gelatinized by a liquid organic compound, preferably a liquid organic nitro-compound, which is a solvent of the nitrated carbohydrate, but which is insoluble in water, and the oxidizing agent is coated with said gelatinized nitrated carbo-hydrate.

30 Nitro-glycerin is an example of a liquid organic compound which may be used and nitro-benzol is an example of an organic nitro compound which may be used. Nitrate of soda and nitrate of ammonia are 35 examples of inorganic oxidizing agents which may be used.

The process by which I produce this product consists in mixing with an ungelatinized nitrated carbo-hydrate, a solid inorganic oxidizing agent impregnated 40 with a small amount of a liquid organic compound, preferably an organic nitro compound, which is a solvent of the nitrated carbo hydrate, but which is

insoluble in water. By small amount I mean an amount insufficient to act upon but a small portion of the nitrated carbo-hydrate. 45

By this process the liquid organic compound is disseminated throughout the entire explosive, thus bringing all the particles of nitrated carbo-hydrate under the action of the organic compound, yet giving to each particle but a small quantity of the organic compound 50 to act upon and thus each particle is substantially only superficially impregnated, the main body of the explosive being unchanged and hence there is substantially no change in the sensitiveness of the explosive.

As an example, I first impregnate 30 parts of nitrate 55 of soda with 10 parts of nitro-benzol and to this add 60 parts of nitro-starch. As another example, I impregnate 25 parts of nitrate of soda with 5 parts of nitro-glycerin and to this add 70 parts of nitro-cellulose. These proportions need not be strictly followed. All that is necessary to bear in mind is that the liquid organic compound should be in a small amount, insufficient to act upon but a small portion of the nitrated carbo-hydrate. 60

Having now fully described my invention, what I 65 claim and desire to protect by Letters Patent is—

1. An uncompressed, waterproof, pulverulent explosive consisting of a mixture of nitrated carbohydrate, a solid inorganic oxidizing agent and a non-volatile liquid organic compound which is a solvent of the nitrated carbohydrate and which is insoluble in water, in which, throughout the explosive, only the surfaces of the particles of nitrated carbohydrate are gelatinized by said liquid organic compound, and the particles of said oxidizing agent are 70 coated with the superficially gelatinized nitrated carbohydrate, substantially as described. 75

2. The process of making a water-proof explosive, which consists in mixing an ungelatinized nitrated carbohydrate with a solid inorganic oxidizing agent impregnated with a small amount of a liquid organic compound which is a solvent of the nitrated carbo-hydrate but which is insoluble in water. 80

In testimony of which invention, I have hereunto set my hand, at Woodbury, on this 26th day of March, 1906.

FLETCHER B. HOLMES.
